UNITED STATES PATENT OFFICE.

CHESTER A. EMERSON, OF WAKEFIELD, MASSACHUSETTS, ASSIGNOR TO CONVERSE RUBBER SHOE COMPANY, OF MALDEN, MASSACHUSETTS.

DESIGN FOR AN OVERSHOE.

Application filed January 13, 1926. Serial No. 16,047. Term of patent 3½ years.

To all whom it may concern:

Be it known that I, CHESTER A. EMERSON, a citizen of the United States, residing at Wakefield, in the county of Middlesex and Commonwealth of Massachusetts, have invented a new, original, and ornamental Design for Overshoes, of which the following is a specification, reference being had to the accompanying drawing, forming part thereof.

Fig. 1 is a perspective of an overshoe, showing my new design, and

Fig. 2 is a rear elevation thereof. The several styles of shading and stippling in the drawings are indicative of contrasting, ornamental tones but not limited to any particular colors.

I claim:

The ornamental design for an overshoe, as shown.

CHESTER A. EMERSON.
